United States Patent Office

Des. 213,048
Patented Dec. 31, 1968

213,048

BULLETIN BOARD OR THE LIKE

Richard McFadyen, Essex Fells, N.J., assignor to Ketcham & McDougall, Inc., Roseland, N.J., a corporation of New Jersey

Filed Oct. 2, 1967, Ser. No. 8,811

Term of patent 14 years

(Cl. D25—1)

FIG. 1

FIG. 2

FIG. 3

FIG. 4

FIG. 1 is the front elevational view of a bulletin board or the like showing my new design;

FIG. 2 is a right side elevational view thereof;

FIG. 3 is a rear elevational view thereof; and

FIG. 4 is a top plan view thereof.

I claim:

The ornamental design for a bulletin board or the like, substantially as shown.
